CUTTER CHAIN

Morris P. Holmes, Claremont, N. H., assignor to
 Sullivan Machinery Company, a corporation of
 Massachusetts

Application May 29, 1933, Serial No. 673,491

21 Claims. (Cl. 262—33)

This invention relates to cutter chains, and more particularly to improvements in cutter chains especially designed to use with coal cutting machines.

5 An object of this invention is to provide an improved cutter chain. A further object is to provide an improved cutter chain having improved bit holding means. A still further object is to provide an improved cutter bit for a cutter 10 chain. Still another object is to provide an improved cutter chain especially designed to use with a narrow cutter bar for cutting relatively narrow kerfs. These and other objects of the invention will, however, hereinafter more fully 15 appear.

In the accompanying drawings there are shown for purposes of illustration two forms which the invention may assume in practice.

In these drawings,—

20 Fig. 1 is a side elevational view of one illustrative embodiment of the improved cutter chain, parts being shown in section to show structural details.

25 Fig. 2 is a cross sectional view taken substantially on line 2—2 of Fig. 1.

Fig. 3 is a perspective view of a cutter chain block.

Fig. 4 is a perspective view of the improved cutter bit.

30 Fig. 5 is a perspective view showing one of the cutter bit clamps.

Fig. 6 is a view similar to Fig. 1 showing a modified form of construction.

Fig. 7 is a cross sectional view taken substantially on line 7—7 of Fig. 6.

Fig. 8 is a perspective view showing a modified form of cutter bit.

In the illustrative embodiment of the invention shown in Figs. 1 to 5, inclusive, there is 40 shown a cutter chain generally designated 1 of a relatively narrow construction associated with a relatively narrow cutter bar 2. The improved cutter chain comprises a series of chain blocks 3 having inwardly projecting ears 4 carrying pins 5.

45 Pivotedly connected to the pins 5 and disposed between the ears 4 of the chain blocks are central straps 6 for connecting the chain blocks together. The chain blocks are provided with lateral guide surfaces 7 engaging the outer guiding edges 8 of 50 the cutter bar, and the cutter bar is provided about its margin with a groove or slot 9 which presents a guiding surface engageable with the inner guide surfaces of the ears and straps of the chain. It will thus be seen that by this improved arrangement of the ears and straps and

the associated cutter bar, a cutter bar and chain of relatively narrow construction is obtained.

The preferred form of cutter bit 10 is herein in the form of a barbed element generally triangular in shape, except for its indented base, and presenting oppositely disposed cutting points 11 and 12 and relatively inclined sides 13 and 14 converging inwardly toward the point 15 of the barbed element. The cutting points 11 and 12 have relatively inclined cutting faces 16 and 17 converging inwardly toward the median line of the bit. The body of the bit is rectangular in cross section. Each chain block 3 is provided with a longitudinal slot 18 for receiving the body of the cutter bit, and the bit block is provided with a 15 longitudinal bore 19 for receiving a holding bolt 20. The ends of the bolt are provided with adjustable nuts 21, 21 for engaging clamp elements 22 and 23 arranged at the opposite ends of the bit block, as shown in Fig. 1. The clamping element 22 is provided with an inward projection 24 having an inclined surface 25 engageable with a corresponding inclined surface 26 on the bit block and the inclined surface 16 of the bit, while the clamping element 23 is provided with an inward 20 projection 27 having an inclined surface 28 engageable with the inclined surface 14 of the bit. It will thus be seen that when the nuts on the bolt 20 are tightened the clamping elements are forced 25 inwardly, thereby clamping the bit within the slot 18 in the bit block.

When the cutting point 11 of the cutter bit becomes dull, the nuts on the bolt 20 may be loosened, thereby releasing the clamping elements 22, 23 to permit removal of the cutter bit from 30 the slot 18 in the bit block. The bit is then turned over with its opposite edge inserted within the slot 18 and the clamping elements thereafter tightened into bit holding position, the cutting point 12 at that time being active while the 35 inclined surface 14 of the bit engages the plane inner surface of the slot 18.

On links upon which the bit is not in the median plane of the chain, the surfaces 26 and the slots 18 may be properly rearranged so that 40 the planes of the surfaces 26 will be perpendicular to the lateral walls of the slots. The members 22 and 23 may be turned about the axis of their holding member 20 to proper position, and may be formed with transversely curved tops to pre- 45 clude projection undesirably above the tops of the link members 3. It is obviously possible to make the surfaces 26 frusto-conical and to make the surfaces 25, 28 also frusto-conically concave, but this, while enabling variation in slot posi- 50 55

tion conveniently, involves making the cutting surfaces 16, 17 curved to permit proper cooperation with the concave surfaces corresponding to surfaces 25, 28. Obviously also offset bit carrying links may be employed, and the bit-carrying head portions and the clamp elements formed as on the link shown, with the off-setting taking care of the bit position, the bit remaining central of the head on each link.

10 In the modification shown in Figs. 6, 7, and 8, the cutter chain is generally designated 30 and the cutter bar 31. The cutter chain comprises a series of bit blocks 32 each having at its outer sides inwardly projecting ears 33. Fixed within aligned openings 34 formed in the ears 33 are rivets 35, while arranged between the ears 33 and pivotally connected to these rivets are side straps 36, 36 for connecting the bit blocks together. Mounted on the rivets 35 and interposed between the side 20 straps 36, 36 are rollers 37 for engaging the inner guiding surface 38 of the cutter bar 31. Formed at the sides of the cutter bar are stepped guiding surfaces 39 and 40 with which the straps 36 and ears 33 of the chain respectively cooperate in the 25 guiding of the chain about the margin of the cutter bar. Each bit block is provided with a series of longitudinal slots 41, herein three in number, arranged radially about a bore 42 extending longitudinally through the bit block.

30 These slots are provided with circular enlargements 43 at their inner sides for the reception of the cylindrical body 44 of the improved cutter bit shown in Fig. 8. Extending centrally through the bore 42 of the bit block is a holding bolt 45 having 35 threaded on its ends adjustable nuts 46, 46 engageable with annular clamping elements 47 and 48 mounted on the bolt, these clamping elements being held tightly against the opposite ends of the bit block by the holding bolt. These clamp- 40 ing elements 47, 48 also engage the opposite end surfaces of the cylindrical body 44 of the cutter bit in the manner shown in Fig. 6, thereby to hold the cutter bits in position within the bit receiving slots 41. This modified form of cutter bit is 45 provided with but a single cutting point 49 having an inwardly and rearwardly inclined cutting face 50 and a rearwardly and inwardly inclined outer surface 51, these faces terminating at the opposite end surfaces 52 and 53 respectively of the bit body. The surfaces 50 and 51 converge 50 outwardly and forwardly to form the cutting point 49.

When it is desired to release the cutter bits from the bit block the holding bolt 45 may be loosened 55 and the clamping elements 47, 48 removed therefrom, thereby to permit axial release of the cylindrical bodies 44 from the bit receiving slots 41. When the bits become dull and have been removed from the bit block new bits may be 60 readily inserted within the bit receiving slots in the bit block and held in position therein by tightening the holding bolt to bring the clamping elements into engagement with the opposite ends of the bit body.

65 As a result of this invention, it will be noted that an improved cutter chain is provided having an improved arrangement and formation whereby a relatively narrow cutter chain and cutter bar construction is attained. It will further be noted that an improved cutter bit is provided having associated therewith improved bit holding means whereby the cutter bit is held in position on the cutter chain in an improved manner. These and other uses and advantages of the

improved cutter chain will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

10 What I claim as new and desire to secure by Letters Patent is:

1. A cutter bit in the form generally of a triangle whose base instead of being plane is made reentrant to provide relatively inclined cutting 15 surfaces which cooperate with the sides of said triangle to provide barbs whose points are cutting points.

2. In a cutter chain, a bit block, a cutter bit in the form of an acute-angled isosceles triangle 20 having a V-notched base, in side elevation, and rectangular in cross section, and having cutting points at the extremities of the legs of the triangle remote from its apex, and means for holding said bit in cutting position on said bit block with 25 one of its cutting points in an outwardly projecting cutting position.

3. Bit holding means for holding a bit in a bit block comprising relatively adjustable clamping elements adjustable relative to the bit block in 30 directions longitudinal of the latter to effect clamping, and engaging different surfaces of a cutter bit and having operating means by which they are simultaneously adjustable toward each other relative to the bit block to clamp the cutter 35 bit in cutting position against a surface of the bit block.

4. Bit holding means for holding a bit in a bit block comprising relatively adjustable clamping elements adjustable relative to the bit block and 40 engaging different surfaces of a cutter bit for holding the latter in cutting position against a surface of the bit block, and a holding bolt for adjusting said clamping elements operative to transmit force to each of the same directly to 45 move them towards each other to effect clamping.

5. A cutter chain comprising a bit block having a longitudinal slot, a cutter bit receivable in said slot and held therein during cutting, a holding 50 bolt carried by said bit block, and a plurality of relatively adjustable clamping elements held in position with respect to the bit block by said holding bolt and engaging the cutter bit for holding the latter in said slot.

6. A cutter bit and holder comprising a bit having a cylindrical body portion and a relatively inclined laterally-offset cutting surface and a holder having a socket for receiving said cylindrical bit body and cooperating clamping means 60 engaging the end surfaces of said cylindrical body.

7. A cutter bit and holder comprising a bit having a cylindrical body portion and an integral lateral portion, said lateral portion having 65 a cutting point formed thereon, and a holder having a socket for receiving said cylindrical bit body and cooperating clamping means engaging the end surfaces of said cylindrical body.

8. A cutter chain comprising a bit block having a longitudinal slot, a cutter bit receivable in said slot, and means for holding said bit in said slot including relatively adjustable holding elements arranged at the ends of said bit block and engaging opposite ends of said bit.

9. A cutter chain comprising a bit block having a series of longitudinal slots, cutter bits receivable in said slots, and means for holding said bits in position in said slots including clamping elements arranged at opposite ends of the bit block and engaging all of said bits.

10. A cutter chain comprising a bit block having a series of longitudinal slots, cutter bits receivable in said slots, and means for holding said bits in position in said slots including clamping elements arranged at opposite ends of the bit block and engaging all of said bits, and a single holding bolt for adjusting said clamping elements in clamping position.

11. A cutter chain comprising a bit block having a longitudinal slot and a parallel longitudinal bore, a cutter bit having a portion receivable in said slot and a cutting portion projecting outwardly from the bit block, clamping members adjustable relative to the bit block at the front and rear sides of the latter and having portions engaging portions of said cutter bit to retain said bit portion in said slot, and a holding bolt extending through said bore and engaging said clamping elements.

12. A cutter chain comprising a bit block having a longitudinal slot and a parallel longitudinal bore, a cutter bit having a portion receivable in said slot and a cutting portion projecting outwardly from the bit block, clamping members adjustable relative to the bit block at the front and rear sides of the latter and having portions engaging portions of said cutter bit to retain said bit portion in said slot, and a holding bolt extending through said bore and engaging said clamping elements, said clamping elements having openings through which said bolt extends and nuts adjustably threaded on the ends of said bolt and engaging the outer surfaces of said clamping elements.

13. A cutter chain comprising a bit block having a longitudinal slot, a cutter bit in the form of a barbed element having relatively inclined cutting portions, one of the cutting portions of the bit receivable in said slot, and adjustable clamping means engaging opposite end portions of the bit for retaining said bit portion in said slot.

14. A cutter chain comprising a bit block having a longitudinal slot, a cutter bit having a cylindrical body portion and a relatively inclined lateral cutting portion, said cylindrical body portion receivable by endwise sliding movement within said slot, and adjustable clamping elements engaging the opposite ends of said cylindrical body portion for preventing longitudinal release of the bit from said slot.

15. A cutter chain comprising a bit block having a longitudinal slot, a cutter bit in the form of a barbed element having relatively inclined cutting portions, a portion of said bit receivable in said slot, and clamping means for holding said bit in said slot comprising a clamping element engaging a surface of one cutting portion and another clamping element engaging another surface of the other cutting portion.

16. A cutter bit generally in the form of an acute-angled isosceles triangle but having its base formed to provide a barb at each end of the latter, said bit having cutting points formed at its end remote from its apex one at the extremity of each barb.

17. A cutter bit in the form of an isosceles triangle but having its base formed to provide a barb at each end of the latter, said bit having cutting points formed at its end remote from its apex, and having further relatively inclined cutting faces terminating at said cutting points and converging at the median line of the isosceles triangle at a point between the base and apex thereof.

18. A cutter bit in the form, in side elevation, of an isosceles triangle having a triangle cut from its base portion, said bit providing cutting points at the extremities of the legs of the first mentioned triangle remote from the angle opposite its base, and further providing relatively inclined cutting faces converging at a line perpendicular to the base and passing through the apex of the first mentioned triangle.

19. In a cutter chain, a cutter block having a longitudinal slot and bit holding means for holding a cutter bit in the bit block slot comprising relatively adjustable clamping elements adjustable relative to the bit block and respectively engaging different surfaces of the cutter bit to clamp the latter in position in said bit block slot.

20. A cutter bit in the form of an isosceles triangle in side elevation save that its base is relatively deeply indented, and rectangular in cross section and having cutting points at the extremities of the legs of the triangle remote from its apex, a straight line extending between said points being of substantially less length than the sides of the triangle.

21. A cutter bit in side elevation generally in the form of an isosceles triangle having its base line of substantially less length than its sides but having short angularly related lines in place of a straight base line and having cutting points at the extremities of the legs of the triangle remote from its apex.

MORRIS P. HOLMES.
